METHODS FOR OXIDATIVELY TREATING FLOUR

Charles G. Ferrari, Evanston, and Kazuo Higashiuchi, Chicago, Ill., assignors to J. R. Short Milling Company, Chicago, Ill., a corporation of Illinois
Filed June 23, 1959, Ser. No. 822,225
8 Claims. (Cl. 99—91)

This invention relates to the treatment of cereal flours and particularly to an improved process for oxidatively treating flours to accomplish bleaching and/or maturing thereof.

Both maturing and bleaching of flours result from oxidative changes in the flour. Maturing can be considered as the same oxidative change which would result from natural aging of the flour for a prolonged period, while bleaching results from the more or less complete oxidation of the carotenoid pigments of the flour to colorless reaction products. Numerous oxidizing agents have been proposed for maturing and bleaching flours. Of these prior art agents, most have been useful to accomplish only maturing or only bleaching. Thus, the bromates, the iodates and the persulfates, all accepted maturing agents, have no bleaching power. Conversely, benzoyl peroxide, one of the more commonly accepted bleaching agents, has no maturing power. The only known agent accepted for commercial use and capable of both maturing and bleaching flours is chlorine dioxide. Chlorine dioxide has, however, proved to be disadvantageous in several respects, the primary disadvantage being that it is too potent, so that an unduly critical control of the amount used must be maintained to avoid over-treatment and damage to color and baking quality of the flour.

The present invention employs a single composition capable of both maturing and bleaching flours, and, in certain embodiments, the invention is adapted to accomplish maturing alone. The invention has a number of important advantages in addition to such flexibility of result. One primary advantage is the fact that the invention does not require such precise control of the amount of oxidatively active material as has been necessary with chlorine dioxide. Thus, our invention makes possible the successful treatment of flour without danger of damaging the flour by overtreatment. A further major advantage of our invention is its ability to gently treat flours in a manner which may be characterized as "accelerated natural aging." Another distinct advantage of the present method is that it employs no materials which are deleterious to human beings. Further, the invention is particularly advantageous in that it makes possible the adequate treatment of flour with only a very minimum of residual chemical agents in the flour after treatment. In this connection, all embodiments of the invention involve at most the addition of only insignificant proportions of non-food materials capable of surviving baking, and certain embodiments of the invention make it possible to treat the flour in such a manner that there will be no residue whatsoever of treating agent after baking.

In copending application Serial No. 15,783, filed concurrently herewith on behalf of Herbert O. Renner, there is disclosed a method for oxidatively treating cereal flours with certain reaction product mixtures derived from acetone and hydrogen peroxide, and with bis-(1,1'-hydroperoxy 1,1'-methyl) diethyl peroxide, a major constituent of such reaction product mixtures. Copending application Serial No. 822,235, filed concurrently herewith by Kazuo Higashiuchi, discloses that the aqueous residue remaining after extraction of such reaction product mixtures with low boiling hydrocarbon solvents, for example, constitutes a superior composition for oxidatively treating flour, such aqueous residues having a materially greater

2

bleaching and maturing action than do the reaction product mixtures as a whole.

The present invention is based upon the discovery that reaction product mixtures derived from methyl ethyl ketone and hydrogen peroxide are markedly superior to any of the aforementioned peroxidic products derived from acetone and hydrogen peroxide.

The flour-treating method of the present invention employs oxidatively active materials obtained by combining methyl ethyl ketone, hydrogen peroxide and water in proportions providing in the initial reaction mixture from .5 to 2.5 moles of hydrogen peroxide for each mole of methyl ethyl ketone and maintaining the resulting initially homogeneous reaction mixture at below 100° C. until, upon standing at normal temperatures, the reaction mixture separates into phases of different specific gravity, the phase of lower specific gravity predominantly comprising methyl ethyl ketone peroxide and free methyl ethyl ketone. Advantageously, an acid catalyst is employed in proportions up to 5% by weight of the reaction mixture to accelerate formation of the peroxidic product desired. Depending upon the relative proportions of methyl ethyl ketone and hydrogen peroxide, the amount of water introduced into the reaction mixture with the hydrogen peroxide or otherwise, the temperature at which the reaction mixture is maintained, and whether or not the reaction mixture is agitated, the reaction time can be selected within the range of from 1 minute to 48 hours.

Though the yield of methyl ethyl ketone peroxides so obtained is sufficiently high to allow use of the entire reaction product mixture as a novel oxidatively active composition for bleaching and maturing flour, in which case water need not be employed, the reaction product mixtures obtained as above described are admirably suited to concentration in various ways. First, the phase of lower specific gravity, amounting to as much as 80% by volume of the total reaction product mixture, is easily recoverable from the higher specific gravity material, only a small proportion of the oxidatively active products remaining in the higher specific gravity material. Next, both the free water and the free methyl ethyl ketone present in the phase of lower specific gravity can be removed easily without undue loss of the desired peroxidic reaction products. Finally, a highly desirable flour bleaching and maturing product consisting essentially of a single acyclic methyl ethyl ketone peroxide is obtainable from the phase of lower specific gravity by extraction with a low boiling hydrocarbon solvent such as hexane or pentane.

Advantageously, the oxidatively active materials derived in the above manner from methyl ethyl ketone and hydrogen peroxide are combined with a carrier material, which can be either a finely particulate solid or a liquid. Where the carrier material is a finely particulate solid, the oxidatively active liquid reaction product mixture can be combined with the solid in such proportions that the liquid amounts to as much as 25% by weight of the combined liquid and carrier.

As has been pointed out, the phase of lower specific gravity resulting from reaction of methyl ethyl ketone and hydrogen peroxide in the manner described contains, in addition to methyl ethyl ketone peroxide, a substantial proportion of unreacted methyl ethyl ketone. Thus, about 20-40% by weight of the phase of lower specific gravity may be free methyl ethyl ketone. Advantageously, this free ketone is left in the liquid material until after the same has been combined with the carrier and is then at least largely removed by volatilization. Thus, employing a particulate solid material as the carrier, the free ketone can be removed by aerating the product, with or without the aid of reduced pressure, at a temperature not exceeding 125° C. Assuming that a relatively large

proportion of the oxidatively active liquid reaction product mixture is combined with a solid carrier material such as a cereal flour, especially good results are obtained by aerating with the aid of vacuum at a temperature of 30-50° C. In general, the temperatures employed during removal of the free methyl ethyl ketone can be increased if (1) the proportion of methyl ethyl ketone peroxides introduced to the carrier material is relatively small or (2) the product introduced to the carrier material contains only small proportions of materials other than acyclic methyl ethyl ketone peroxides and free ketone.

While effective flour-treating compositions can be prepared from initial reaction mixtures in which the proportion of hydrogen peroxide ranges from .5 to 2.5 moles per mole of methyl ethyl ketone, superior results are obtained when the proportion of hydrogen peroxide ranges from 1 to 1.5 moles per mole of ketone. Such proportions provide improved reaction rates and greater yields of methyl ethyl ketone peroxides. Within the limits specified, increasing the relative proportion of methyl ethyl ketone will increase the volume of the lower specific gravity material, also increasing the proportion of free ketone therein, while an increase in the relative proportion of hydrogen peroxide will increase the volume of the higher specific gravity product, also increasing the proportion of free hydrogen peroxide therein.

The rate of reaction and the yield of peroxides also depends upon the concentration of hydrogen peroxide in the initial reaction mixture. In this connection, the hydrogen peroxide is preferably employed in the form of an aqueous solution containing at least 25% by volume hydrogen peroxide, and considerable water is thus introduced into the reaction mixture. While the presence of water is not essential to the reaction, it is required in order that the reaction product mixture will separate into phases of lower and higher specific gravity, the phase of higher specific gravity retaining those compounds which are more soluble in water. In order to obtain the advantages of phase separation and still maintain good reaction rates and yields, the proportion of water in the initial reaction mixture, whether added with the hydrogen peroxide or otherwise, is kept in the range of 10-50% by volume, based on the total reaction mixture. Thus, an aqueous hydrogen peroxide solution should not be used which is so dilute as to provide, for the particular proportion of hydrogen peroxide chosen, an amount of water in excess of 50% of the volume of the initial reaction mixture. On the other hand, if an amount of water less than 10% of the volume of the initial reaction mixture is provided by addition of the hydrogen peroxide solution, additional water should be added to provide the minimum amount necessary for phase separation.

The reaction is rather strongly exothermic initially. However, if the reaction mixture is cooled for an initial period sufficient to remove the exothermic heat, cooling can then be terminated and the reaction mixture will remain cool for the balance of the reaction period.

Best yields of methyl ethyl ketone peroxides are obtained in the shortest reaction time when the reaction mixture is maintained at a temperature within the range of 15-70° C. Within such temperature range, and with the proportion of hydrogen peroxide being from 1 to 1.5 moles per mole of methyl ethyl ketone, the other process variables being controlled as hereinbefore discussed, the phase of lower specific gravity will amount to from 35-80% by volume of the reaction product mixture, as much as 80% by weight of such lower specific gravity phase being methyl ethyl ketone peroxides, the predominant portion of the organic peroxide content being an individual acyclic methyl ethyl ketone peroxide as yet not completely characterized.

While the reaction proceeds at temperatures up to 100° C., the yield of the desired peroxides obtained in a given reaction time decreases as the temperature is raised above

about 80° C. The reaction rate is also decreased when the temperature of the reaction mixture is decreased below 15° C. but, by extending the reaction time, good yields can be obtained at temperatures on the order of 10° C. and lower.

Excellent results are obtained by combining the reactants at room temperature, cooling the reaction mixture initially to absorb exothermic heat, and then allowing the reaction mixture to continue for the selected time period at room temperature.

When the reaction is carried out at elevated temperatures, phase separation is accomplished by cooling the liquid product to about room temperature.

While other acid catalysts can be employed, best results have been obtained with the mineral acids in amounts up to about 5% by weight of the reaction mixture. Among the mineral acids, the ability of the acid to catalyze the reaction varies between the individual acids. Thus, while excellent reaction rates and yields are attained by using 0.04-1% by weight of hydrochloric or sulfuric acid, the equivalent results are achieved with 0.4-4% of phosphoric acid. Practical reaction times on the order of 1 minute are provided when 1% of hydrochloric or sulfuric acid is employed and when 4% of phosphoric acid is employed. Without catalyst, the reaction time can be extended to 48 hours.

Solid, particulate, edible carriers which are suitable for preparing compositions useful in accordance with the invention include food starches, particularly corn starch, dextrines, wheat flour, defatted wheat flour, heat-treated wheat flour, pre-oxidized starches and flours, vegetable proteins, such as wheat gluten and soybean protein, and edible inorganic materials, such as inorganic phosphates and calcium sulphate, which are inert to peroxides. The particulate carrier material should provide a porous structure or a large effective surface area so that the oxidatively active liquid can be retained by absorption and/or adsorption.

In treating the flour, the compositions prepared in accordance with the procedure hereinbefore described can be sprayed as liquids directly into the flour while the flour is being agitated. When a carrier-supported composition is employed, simple blending procedures are used and the carrier-supported composition is ordinarily left in the flour after the oxidative treatment is completed. The relative proportion of the oxidatively active compositions employed in accordance with the invention depends upon whether only maturing, or both maturing and bleaching, is desired and also upon the extent to which maturing or bleaching and maturing are to be accomplished. Ordinarily, the amount of oxidatively active methyl ethyl ketone peroxide composition employed is such as to provide a hydrogen peroxide equivalent value on the order of a few thousands of a percent of the weight of the flour being treated. For obtaining mild maturing of the flour, the hydrogen peroxide equivalent value can be less than 0.001% by weight. Assuming that no additional oxidative agents are employed, bleaching can be accomplished with quantities of the methyl ethyl ketone peroxide composition providing hydrogen peroxide equivalent values in the general range of 0.002% to 0.006% or higher, depending upon the nature of the flour being treated.

EXAMPLE 1

An initially homogeneous liquid reaction mixture was prepared by blending 25 ml. aqueous hydrogen peroxide solution (37% H₂O₂ by volume), 50 ml. methyl ethyl ketone and 0.05 ml. concentrated sulfuric acid. The reaction mixture was maintained substantially at room temperature for 1 hour, at the end of which time the liquid was separated into distinct upper and lower layers. The upper phase was recovered and the proportion of free methyl ethyl ketone therein removed by maintaining the liquid over a hot water bath for 30 minutes. The

resulting liquid product was freed of water by means of anhydrous sodium sulfate. By titration, the resulting product was found to have a hydrogen peroxide equivalent content of 32.6% by weight.

A carrier-supported composition suitable for bleaching flour was prepared by blending 40 ml. of the liquid product so obtained with 100 g. of dry, food grade corn starch and drying the mixture at room temperature under an exhaust hood for 30 minutes. The carrier-supported composition, hereinafter referred to as composition A, was found to have a hydrogen peroxide equivalent content of 4.9% by weight.

To determine the relative effectiveness of the bleaching and maturing composition of this example, a control composition was prepared, in accordance with the aforementioned application Serial No. 15,783, by blending equi-molar proportions of acetone and aqueous hydrogen peroxide (60% by volume) and refluxing the resulting liquid reaction mixture over a water bath for one hour, the resulting reaction product mixture being intimately combined with food grade corn starch as a carrier material. The control composition is hereinafter referred to as composition B.

Equal quantities of a commercially available unbleached bread wheat flour were measured out, one quantity being combined with a sufficient proportion of composition A to incorporate in the flour a hydrogen peroxide equivalent of 0.0045% by weight and the other quantity of flour being combined with a sufficient proportion of composition B to incorporate in the flour the same hydrogen peroxide equivalent. The two quantities of flour were then allowed to stand at room temperature in closed containers and the carotene content of the flour was measured periodically. The relative bleaching abilities of compositions A and B are plotted in the chart of FIG. 1, wherein it will be noted that composition A of this example is, at two days, approximately 100% more effective as a bleaching agent than is control composition B.

EXAMPLE 2

An initially homogeneous liquid reaction mixture was prepared by blending 57 ml. of aqueous hydrogen peroxide solution (60% H_2O_2 by volume), 89.5 ml. of methyl ethyl ketone and 5 ml. of 1 N hydrochloric acid. The reaction mixture was maintained substantially at room temperature for a period of 30 minutes, being agitated continuously during that period by means of a vibrating magnetic stirrer. The resulting liquid was neutralized by addition of 5 ml. of 1 N sodium hydroxide and was then allowed to stand until it had separated into distinct upper and lower phases. The upper phase was recovered by means of a separatory funnel.

Of the recovered liquid, 50 ml. was extracted with 500 ml. of hexane, extraction being carried out at room temperature with continual agitation for 30 minutes and the hexane then removed under vacuum, leaving as the residue a viscous liquid product.

A carrier-supported composition suitable for use in bleaching flour and the like was prepared by blending 2 g. of the viscous liquid product with 10 g. of dry, food grade corn starch and aspirating the resulting blend for 30 minutes at room temperature with air to remove any remaining traces of hexane or other volatiles. The resulting product was found to have a hydrogen peroxide equivalent content of 4.35% by weight, and is herein-after referred to as composition C.

For purposes of comparison, a control composition was prepared in accordance with the aforementioned co-pending application Serial No. 15,783 by blending equi-molar proportions of acetone and aqueous hydrogen peroxide (60% H_2O_2 by volume) and aging over a boiling water bath for one hour, the resulting reaction product mixture then being extracted five times with equal volumes of hexane, the extracts combined and the solvent removed to provide a composition predominantly

comprising bis-(1,1'-hydroperoxy 1,1'-methyl) diethyl peroxide. The product was intimately combined with food grade corn starch, the resulting composition being herein-after referred to as composition D.

Equal samples of a commercially available unbleached bread wheat flour were measured out. A sufficient proportion of composition C was added to one sample to incorporate therein a hydrogen peroxide equivalent content of .006% by weight. Similarly, a sufficient proportion of composition D was blended with the other sample of flour to introduce therein the same hydrogen peroxide equivalent. The two samples of flour were then allowed to stand at room temperature in closed containers and the carotene content of the two samples was determined from time to time, the results being illustrated in FIG. 2. Here, it will be noted that composition C is vastly superior to composition D, providing adequate bleaching, for commercial purposes, within a period of approximately two days.

In considering Examples 1 and 2, it is to be understood that these examples compare the compositions of the present invention with the corresponding compositions of application Serial No. 15,783, which application discloses the only other known oxidative agents, aside from chlorine dioxide, which are capable of both maturing and bleaching wheat flour. In Example 1, the comparison is between compositions which are prepared by using substantially the entire reaction product mixture, while the comparison in Example 2 is between products each predominantly comprising only a single peroxidic compound. In the case of composition D of Example 2, the single compound is bis-(1,1'-hydroperoxy 1,1'-methyl) diethyl peroxide. In the case of composition C of Example 2, the peroxidic compound of methyl ethyl ketone has not as yet been completely characterized.

EXAMPLE 3

To demonstrate the effect of treatment of flour in accordance with the invention on bread baked from the flour, flour samples of a commercially available unbleached bread wheat flour were taken, sample 1 being used as control with no bleaching or maturing agent added thereto, and samples 2, 3 and 4 being treated by addition of composition A of Example 1 in proportions providing in the flour samples hydrogen peroxide equivalent values of .003, .0045 and .006% by weight, respectively. The flour samples were allowed to stand in closed containers for 15 days at room temperature and white bread was then made by preparing separate doughs from each flour sample by a conventional sponge-dough procedure, using the following formula:

	Sponge	Ingredient	Dough, g.
55	420 g.	Flour	280
	17.5 g.	Water	-----
	2.0 g.	Yeast	-----
		Yeast food	-----
		Milk solids	21
40		Salt	14
		Sugar	35
45		Lard	21
50			
60			

Baked under identical conditions, the bread from the four flour samples scored as follows:

65	Flour sample	Level of treatment with comp. A of Example 1, percent	Loaf volume (in cc.)	Break and shred (3)	Grain (10)	Crumb color (10)	Texture (15)
70	1	Control	2,400	1.3	6.0	5.0	10.0
	2	.003	2,450	1.5	6.5	6.0	11.0
	3	.0045	2,540	2.1	7.0	7.0	11.0
	4	.006	2,690	2.4	8.0	8.0	11.0

It is thus apparent that the internal characteristics of bread prepared from flour treated in accordance with the invention improved proportionately as the level of treatment increased from .003% by weight of the flour to .006%. The improvement in crumb color is that which would be expected to result from bleaching of the magnitude described with reference to Example 1. The improvement in loaf volume and grain is that which would be expected to result from adequate maturing of the flour.

Analytical procedures

Total peroxide content of the reaction products prepared as hereinbefore described can be determined by (1) potassium iodide-thiosulfate titration, using aqueous sulfuric acid (1 part H_2SO_4 to 9 parts water by volume) or (2) modified Wheeler titration, omitting chloroform. The results are expressed as the hydrogen peroxide equivalent value.

Free hydrogen peroxide is determined as follows:

Step 1.—A 0.05 g. sample of the material to be analyzed is combined with 25 ml. water and 1 mg. catalase and allowed to react for 30 min. *Step 2.*—25 ml. aqueous sulfuric acid (1 part conc. H_2SO_4 to 4 parts water by volume) is added, followed by 1 ml. saturated potassium iodide solution. *Step 3.*—The solution is titrated with standard thiosulfate to give the total organic peroxide content, free hydrogen peroxide having been destroyed by the catalase in step 1. *Step 4.*—Subtract the total organic peroxide content, determined in step 3, from the total peroxide content, the difference being free hydrogen peroxide.

Free methyl ethyl ketone is measured as follows:

Step 1.—Combine 200 ml. of .3% fresh hydroxylamine hydrochloride and a .2 g. sample of the material to be analyzed and allow to stand for 3 min. *Step 2.*—Titrate with standard .1 N sodium hydroxide until the pH is brought to the original pH of the hydroxylamine hydrochloride solution. *Step 3.*—Compute percent free methyl ethyl ketone as follows:

(Titration value) (0.00777) (100)

Sample weight

= percent methyl ethyl ketone

Characterization of methyl ethyl ketone peroxide constituting predominant proportion of reaction product

While not as yet identified with complete accuracy, the acyclic methyl ethyl ketone peroxide which constitutes the predominant proportion of the product resulting from reacting methyl ethyl ketone and hydrogen peroxide in accordance with the method hereinbefore described appears to be bis-(1,1'-hydroperoxy 1,1'-ethyl) diethyl peroxide, having the formula

The compound titrates in the same fashion as bis-(1,1'-hydroperoxy 1,1'-methyl) diethyl peroxide, the corresponding compound derived from acetone.

Active oxygen was determined for the methyl ethyl ketone peroxide in question in the following manner: The phase of lower specific gravity produced in accordance with Example 1 was recovered and extracted with hexane, the solvent and free ketone then being removed from the extract by fractional distillation under vacuum. The residue from the distillation step was then dissolved in cold hexane, dried with anhydrous sodium sulfate and cooled to $-70^{\circ} C.$ on a Dry Ice-ethyl alcohol bath, causing the peroxide to be thrown down as a heavy, oily liquid. The hexane was decanted, the purified product recovered, and the procedure repeated. The active oxygen content of the finally recovered, purified product was

determined by titration with .1 N thiosulfate and computed in accordance with the following formula:

(Titration value) (.0008) (100)

5 Sample weight

= Percent active O_2 by weight

The active oxygen was found to be 22.4% by weight, .2% less than the theoretical active oxygen content of bis-(1,1'-hydroperoxy 1,1'-ethyl) diethyl peroxide.

10 In similar determinations, the material thrown down from the cold hexane solution has varied from a solid to a heavy liquid at room temperature, apparently due to the presence of varying, small amounts of impurities.

15 Both the active oxygen determination and the fact that the corresponding cyclic compounds are not titratable by the thiosulfate procedure indicate that the product is the acyclic dimeric peroxide of methyl ethyl ketone.

We claim:

20 1. The method for oxidatively treating flour to at least mature the same comprising introducing into the flour a small but effective proportion of an oxidatively active material having a substantial peroxide content predominantly constituted by acyclic peroxidic reaction products of methyl ethyl ketone and hydrogen peroxide which are titratable with thiosulfate, the proportion of said material employed providing a hydrogen peroxide equivalent value, based on the weight of the flour, of at least about 0.001%.

25 2. The method for oxidatively treating flour to at least mature the same comprising introducing into the flour a small but effective proportion of an oxidatively active liquid reaction product mixture, obtained by reacting methyl ethyl ketone and hydrogen peroxide at below $100^{\circ} C.$, said reaction product mixture having a substantial peroxide content predominantly constituted by acyclic methyl ethyl ketone peroxide, the proportion of said reaction product mixture employed providing a hydrogen peroxide equivalent value, based on the weight of the flour, of at least about 0.001%.

30 3. The method of claim 2 wherein said liquid reaction product mixture is supported on a particulate carrier.

35 4. The method of claim 3 wherein said carrier is a finely particulate cereal product.

40 5. The method for oxidatively treating flour to at least mature the same comprising introducing into the flour a small but effective proportion of an oxidatively active material prepared by (1) combining methyl ethyl ketone, aqueous hydrogen peroxide and 0-5% of an acid catalyst to provide an initially homogeneous liquid reaction mixture containing 10-50% by volume water and .5-2.5

50 moles of hydrogen peroxide per mole of methyl ethyl ketone, (2) maintaining such reaction mixture below $100^{\circ} C.$ for from 1 minute to 48 hours and thereby causing the methyl ethyl ketone and hydrogen peroxide to react to form an acyclic methyl ethyl ketone peroxide, (3) allowing the resulting liquid reaction product mixture to separate into phases of lower and higher specific gravity, (4) recovering the phase of lower specific gravity, and (5) at least materially reducing the amount of free water and ketone in such recovered phase to provide said

55 60 oxidatively active material, the proportion of said oxidatively active material employed providing a hydrogen peroxide equivalent value, based on the weight of the flour, of at least about 0.001%.

65 6. The method of claim 5 wherein said oxidatively active material is supported on a finely particulate, edible, solid carrier material.

70 7. The method for oxidatively treating flour to at least mature the same comprising introducing into the flour a small but effective proportion of the acyclic peroxidic compound produced by (1) combining methyl ethyl ketone, aqueous hydrogen peroxide and 0-5% of an acid catalyst to provide an initially homogeneous liquid reaction mixture containing 10-50% by volume water and .5-2.5 moles of hydrogen peroxide per mole of methyl ethyl ketone, (2) maintaining such reaction mixture be-

low 100° C. for from 1 minute to 48 hours and thereby causing the methyl ethyl ketone and hydrogen peroxide to react to form an acyclic methyl ethyl ketone peroxide, (3) allowing the resulting liquid reaction product mixture to separate into a phase of lower specific gravity, containing said methyl ethyl ketone peroxide in solution, and a phase of higher specific gravity, (4) recovering said phase of lower specific gravity, and (5) extracting said methyl ethyl ketone peroxide from said recovered phase, the proportion of said acyclic peroxidic compound employed providing a hydrogen peroxide equivalent value, based on the weight of the flour, of at least about 0.001%.

8. The method for oxidatively treating flour to at least mature the same comprising introducing into the flour a small but effective proportion of an oxidatively active material wherein at least a material proportion of the oxidatively active content is constituted by an acyclic

hydroperoxidic compound derived from hydrogen peroxide and methyl ethyl ketone, titratable by thiosulfate and having an active oxygen content of about 22.4%, the proportion of said oxidatively active material employed providing a hydrogen peroxide equivalent value, based on the weight of the flour, of at least about 0.001%.
